UNITED STATES PATENT OFFICE.

GUSTAV FUEHLER, OF VERDON, SOUTH DAKOTA.

WATER EXPLOSION-ENGINE.

1,226,500.

Specification of Letters Patent.

Patented May 15, 1917.

Application filed August 9, 1916. Serial No. 113,990.

To all whom it may concern:

Be it known that I, GUSTAV FUEHLER, a citizen of the United States, residing at Verdon, in the county of Brown, State of 5 South Dakota, have invented certain new and useful Improvements in Water Explosion-Engines; and I do hereby declare the following to be a full, clear, and exact description of the invention, such as will enable others skilled in the art to which it appertains to make and use the same.

This invention relates to engines and has special reference to an explosion engine using water, the engine being so arranged 15 that upon the introduction of water into the cylinder the water bursts into steam and drives the usual piston.

The principal object of the invention is to provide an improved and simplified engine wherein the water is introduced directly into the cylinder in its liquid state and is there caused to burst into steam for the propulsion of the cylinder.

A second important object of the invention 25 is to provide means whereby water is introduced into an engine cylinder and strikes a hot plate within the cylinder so that it bursts at once into steam and acts substantially as an explosive engine.

30 A third important object of the invention is to provide an improved arrangement of engine of this class wherein the plate is kept hot by means of electricity.

With the above and other objects in view, 35 as will be hereinafter apparent the invention consists in general of certain novel details of construction and combinations of parts hereinafter fully described, illustrated in the accompanying drawings, and specifically claimed.

In the accompanying drawing, like characters of reference indicate like parts in the several views, and:—

Figure 1 is a longitudinal section through 45 an engine constructed in accordance with this invention.

Fig. 2 is an enlarged detail side elevation of the heating element, and hot plate.

Fig. 3 is an enlarged detail section on 50 the line 3—3 of Fig. 1.

Fig. 4 is a detail section on the line 4—4 of Fig. 2.

In carrying out the objects of this invention there is provided an engine having the 55 usual base 10, shaft 11 and fly wheel 12. Mounted on the base 10 is a cylinder 13

wherein reciprocates a piston 14 connected to a rod 15, the latter being in turn connected by means of a connecting rod 16 to the pin 17 of the fly wheel 12. The cylinder 13 is so arranged that the piston does not approach closely to the back head 18, considerable space being left between this back head and the piston 14 when the piston is at its rearmost position.

Located at each side of the cylinder in the space between the piston and the back head 18 is a bracket 19 and on these brackets 19 is supported a resistance coil carrying member 20 which is preferably of refractory insulating material such as porcelain or the like and is provided with a spiral groove 21 extending from one end to the other around the member 20. Seated in the bottom of the groove 21 is a resistance wire 22 which leads out of the cylinder through insulating bushings 23 being connected by wires 24 to a battery 25 or other suitable source of electricity. Thus this resistance coil is heated by the current flowing through the wires 24. Resting on top of the member 20, is a metallic plate 26 which forms the flash plate of the device. Extending through a stuffing-box 27 in top of the cylinder is a water pipe 28 provided with a jet nozzle 29 which is located centrally over the plate 26. This water pipe 28 is controlled by a hand valve 30 and is also provided with a valve 31 which is controlled by the engine. In order to effect the control of the valve 31 this valve is provided with an operating arm 32 which is connected by a link 33 to a rod 34 carried in one or more suitable guides 35 mounted on the cylinder. On the rod 34 is a collar 36 which is held in adjusted position by means of a set screw 37 and between this collar 36 and one of the guides 35 is a spring 38 which normally holds the rod in the position shown in Fig. 1, which position is just prior to the admission of water. There is also provided on the rod 34 a collar 39 which is held in adjusted position by means of a set screw 40. On the piston rod 14 is fixed an arm 41, the arm being held in adjusted position on the rod by a set screw 42. This arm 41 has in its outer end a sleeve 43 through which the rod 34 slides. In the operation of the device the collar 39 and arm 41 are so adjusted on their respective rods that just prior to the extreme rear movement of the

100

105

110

piston 14 the sleeve 43 will contact with the collar 39 and push the rod 34 toward the rear of the cylinder 13 so as to swing the valve arm 32 and open the valve 31 thus admitting a jet of water which strikes on the plate 26, and the latter being hot immediately bursts into steam which drives the piston 14 forward.

Extending from the bottom of the cylinder is an exhaust pipe 44 which is controlled by a valve 45 having an arm 46. This arm 46 is connected to a rod 47 which slides through suitable bearings in the base of the engine and is in turn connected to a rod 47' 55 slideable through a rocking bearing 48. On the rod 47 is a collar 49 which is held in adjusted position by means of a set screw 50 and between this collar and one of the bearings in the base is a spring 51 which normally holds the rod in the position shown in Fig. 1 and consequently the valve 45 closed. On the rod 47' is a roller 52 which bears against a cam 53 carried by the shaft 11 and this cam is so arranged that as the piston 14 moves back after the explosion stroke the cam will effect movement of the rod 47 in such direction as to open the valve 45 the cam being further arranged to permit closing of this valve just before the piston 14 reaches its rearmost position.

In the operation of the device as the water is admitted to the hot plate it bursts into steam and drives the piston forward. As the piston moves forward the valve 31 is closed, the valve 45 remaining closed during this forward movement. As the piston begins to move backward under the inertia of the fly wheel 12 the valve 45 opens and allows the steam to exhaust through the pipe 44. Upon the piston approaching its rearmost position the valve 45 closes and the valve 31 is opened so that a repetition of the explosion and forward driving of the piston 14 occurs.

It is obvious that while a battery 25 has been shown in the present instance this battery may be replaced by any suitable source of electrical energy such as a dynamo or the like and the battery is merely to be taken as typical of any desired source of energy.

It will also be obvious that while the device has been shown as applied to a single cylinder engine it may be applied to the different cylinders of a multi-cylinder engine having the cranks set at different angles, the arrangement in each individual cylinder being precisely that shown in the single cylinder with the different cams 53 set at the appropriate angles to effect the proper opening and closing of the valves 31 and 45 respectively.

The water supplied from the pipe 28 may be supplied under pressure or may flow from the ordinary city mains or from a third tank as desired and the pipe 28 is to be taken as typical of any preferred form of water supply which may be found convenient.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new is:—

A flash unit for steam engine cylinders of the flash type comprising a pair of supports adapted to be secured opposite each other within a cylinder, a heating coil carrying member adapted to fit between said supports and be carried thereby, said member having a spiral groove extending therearound from one end to the other and being formed of a refractory insulating substance, a resistance wire wound on said member in said groove, and a flash plate supported on top of said member out of contact with the resistance wire and in juxtaposition therewith.

In testimony whereof, I affix my signature, in the presence of two witnesses.

GUSTAV FUEHLER.
